UNITED STATES PATENT OFFICE.

DAVID H. WATTS, JR., OF PHILADELPHIA, PENNSYLVANIA.

DESIGN FOR A TILE.

SPECIFICATION forming part of Design No. 35,691, dated February 4, 1902.

Application filed December 20, 1901. Serial No. 86,714. Term of patent 14 years.

To all whom it may concern:

Be it known that I, DAVID H. WATTS, Jr., a citizen of the United States, residing in Philadelphia, Pennsylvania, have invented and produced a new and useful Design for a Tile, of which the following is a specification.

My design for a tile is fully illustrated in the accompanying drawing, in which the figure shown is a perspective view of the tile forming the subject of my invention.

The body 1 of the tile is triangular in general contour, having at each corner the member 2, with rounded face 3 and straight portions 4. Between the corner members 2 of the tile are rounded depressions 5 and on each

side of the depressions are straight portions 6, which are at an angle to and join the straight portions 4. The tiles thus formed are interchangeable and match each other when laid.

I claim—

The design for a tile substantially as described and as shown in the accompanying drawing.

In testimony whereof I have signed my name to this specification in the presence of 25 two subscribing witnesses.

DAVID H. WATTS, JR.
